UNITED STATES PATENT OFFICE.

JAMES T. COWLEY, OF LOWELL, MASSACHUSETTS, ASSIGNOR TO THE LAMSON CONSOLIDATED STORE SERVICE COMPANY, OF NEWARK, NEW JERSEY.

CONVEYING APPARATUS.

SPECIFICATION forming part of Letters Patent No. 608,581, dated August 9, 1898.

Application filed February 17, 1898. Serial No. 670,623. (No model.)

To all whom it may concern:

Be it known that I, JAMES T. COWLEY, of Lowell, in the county of Middlesex and State of Massachusetts, have invented certain new 5 and useful Improvements in Conveying Apparatus, of which the following is a specification.

My invention relates to improvements in cable carriers, and is in the nature of an improvement upon the apparatus shown, described, and claimed in an application filed 10 by me on August 20, 1896, Serial No. 603,332.

The object of my invention is to provide means at each station for removing the last 15 carrier arriving at the station without removing the other carriers that may be in said station, and, further, to gradually check the momentum of the carrier as it travels along the branch track into the station.

20 My invention consists of certain novel features hereinafter described, and particularly pointed out in the claims.

In the accompanying drawings, which illustrate a construction for embodying my invention, Figure 1 is a side view in perspective and illustrating my improvement as applied to cable carrier apparatus of the usual construction. Fig. 2 is a cross-sectional view taken on the line 2 2, Fig. 1, looking in the 25 direction indicated by the arrow. Fig. 3 is a cross-sectional view taken on the line 3 3, Fig. 1, looking in the direction indicated by the arrow. Figs. 4 and 5 represent, respectively, plan and end views of a carrier. Fig. 6 is a 30 plan view of the track-section for receiving the carriers switched at the stations to which they belong and showing a carrier entering said track-section. Fig. 7 is a view similar to Fig. 6 except that the carrier is shown at 35 the other end of the track-section.

40 Like letters of reference refer to like parts throughout the several views.

Referring to Fig. 1, in which there is illustrated a station on the line of a cable carrier apparatus of the construction shown in the above-mentioned application, A represents a branch track from the usual main return-track and is composed of two opposite rails A'. This branch track A is supported by the

brace B both at its upper and its lower ends, 50 and a suitable brace A² holds said rails in their relative positions. Located in alinement with the lower end of the branch track A is a track-section C, composed of the two opposite rails C' and supported at the end which 55 is in alinement with said branch track by the bracket C², which is secured to both of said rails C'. In the opposite sides of said bracket C² are located slots C³, into which project the pins C⁴, mounted on the lower 60 portion of the brace B, and by means of said pins and slots the track-section is guided in its vertical movements. From the rear side of said bracket C² there projects rearwardly the pin C⁵, and under said pin C⁵ and over the 65 two pins C⁴ is a spring C⁶, which is adapted normally to hold in its upper position the bracket C², with the rails C' of the track-section C in alinement with the rails A' of the branch track A, so that a carrier switched 70 on the said branch track will pass onto the rails C'. The opposite ends of these rails are carried by opposite arms D', which are mounted on the pin D², having a bearing in the lugs D³ on the lower portion of the brace 75 D. On each arm D' there is a lug D⁴, to which the opposite ends of the springs D⁵ are connected, so that normally said spring holds the upper ends of said arms in contact, as shown in Fig. 2. By this arrangement 80 the distance between the opposite rails C' gradually reduces from the brace B to the brace D, so that the friction between the friction-rollers G³ and the rails C' increases as the carrier travels toward the brace D, and 85 consequently the momentum of the carrier is checked and the carrier is gradually stopped as the rails C' gradually separate against the tension of the spring D⁵, as illustrated in Figs. 5 and 6.

90 The carrier E, which is similar to that shown, described, and claimed in Letters Patent issued to the Lamson Consolidated Store Service Company, of Newark, New Jersey, as my assignee, numbered 574,715, and dated 95 January 5, 1897, is provided with a cover E', held in a closed position by a suitable spring-catch, which is adapted to be operated by

the push-button E² to release the cover E', and the spring E³ will throw the cover E' up and open the interior of the carrier.

E⁴ represents suitable pins on the carriers, 5 by which the carriers are switched to their respective stations. These pins E⁴ are placed in different positions on the carriers to correspond with switch-guides at different stations along the line, so that the carriers may be 10 switched at the stations to which they belong.

The lever F is provided with a pin F', on which the gripping-jaws F² are pivotally mounted, and said lever is journaled in suitable lugs F⁵ on the rear side of the carrier.

15 These jaws F² are each provided with a cam-slot F⁴, working on the pin F³, secured to the carrier, and of such form that the jaws will be open as the lever F is lowered in position to cause the jaws F² to engage with the usual 20 cable II², by which the carriers are propelled along the usual forwarding and return tracks. When the lever F is raised, the spring F⁶, located at the back of the carrier and around the lever F, closes the jaws F² upon the cable II².

25 G is a plate secured to the bottom of the carrier by screws G', and said plate is provided with ears G², which are adapted to pass under the rails and hold the carriers thereon, as said ears extend beyond the rails.

30 G³ represents friction-rollers mounted upon the screw G' and free to revolve thereon, and the object of these rollers is to prevent friction when the carrier is traveling along the track, around the corners, and into the stations.

35 The forwarding-track II, which is composed of the opposite rails II', is supported by the braces B and D as it passes through the station, and near the center of said track both 40 rails are cut away, as shown at I, to allow the ears G² on the plate G to pass under said rails, and said rails are rigidly secured by the cross-piece I'.

45 The carriers are sent along the forwarding-track II from the salesman to the cashier's desk and are returned by the cashier on the usual return-track, on which is provided the usual switching arrangement—for example, as shown in the application above referred 50 to—so that the carriers belonging to a certain station are switched to that station and, as illustrated in the present drawings, around the branch track A onto the track-section C, and the momentum of the carrier is checked 55 and the carrier is stopped by reason of the arms D' and the spring D⁵.

Usually at each station there are three or four carriers by which cash is forwarded by the salesman to the cashier, and after the change 60 is made the carrier is returned by the cashier to the salesman and, switching onto the branch track from the return-track, comes in rear of the other carriers on the track-section C. In order to obtain the last carrier and 65 return the change to the purchaser, the operator takes hold of the last carrier on

the track-section C and slides it toward the brace B and rails A', and the carrier, being pulled downwardly, is slid off said track-section C, and upon the removal of the carrier 70 the spring C⁶ returns the rails C' into alignment with rails A' to receive the next carrier switched at the station. This feature of removing the last carrier at the station without disturbing the other carriers is not broadly 75 claimed in this application, as it is shown, described, and broadly claimed in the application above referred to.

I do not limit myself to the arrangement and construction shown, as the same may be 80 varied without departing from the spirit of my invention.

Having thus ascertained the nature of my invention and set forth a construction embodying the same, what I claim as new, and 85 desire to secure by Letters Patent of the United States, is—

1. In a conveying apparatus, a forwarding-track, a branch return-track, a track-section 90 normally in alignment with said branch return-track and adapted to receive the diverted carriers and having its end nearest the branch return-track adapted to be moved from its alignment to permit the removal of the carriers therefrom, and yielding means connected 95 to said track-section for gradually checking the momentum of a carrier traveling along said track-section.

2. In a conveying apparatus, a forwarding-track, a branch return-track, a track-section 100 normally in alignment with said branch return-track and adapted to receive the diverted carriers and having its end nearest the branch return-track adapted to be moved from its alignment to permit the removal of the carriers therefrom, yielding means connected to 105 said track-section for gradually checking the momentum of a carrier traveling along said track-section, and means for returning said track-section to alignment with said branch 110 return-track.

3. In a conveying apparatus, a forwarding-track, a branch return-track composed of two opposite rails, a track-section composed of two opposite rails normally in alignment 115 with the opposite rails of the branch return-track and adapted to receive the diverted carriers and having its end nearest the branch return-track adapted to be moved from said alignment to permit the removal of the carriers therefrom, and a spring connected to 120 said opposite rails of said track-section and adapted to yield and gradually check the momentum of a carrier traveling along said track-section.

4. In a conveying apparatus, a forwarding-track, a branch return-track composed of two opposite rails, a track-section composed of two opposite rails normally in alignment 125 with the opposite rails of the branch return-track and adapted to receive the diverted carriers and having its end nearest the branch 130

return-track adapted to be moved from said alinement to permit the removal of the carriers therefrom, a spring connected to said opposite rails of said track-section and adapted to yield and gradually check the momentum of a carrier traveling along said track-section, and means for returning said track-section to alinement with said branch return-track.

In testimony whereof I have signed my name to this specification, in the presence of two subscribing witnesses, this 8th day of February, 1898.

JAMES T. COWLEY.
